DESIGN FOR A COMBINATION KNIFE AND FORK

Lillian Schumacher, Brooklyn, N. Y.

Application November 4, 1941, Serial No. 104,022

Term of patent 3½ years

To all whom it may concern:

Be it known that I, Lillian Schumacher, a citizen of the United States and resident of Brooklyn, New York, in the county of Kings and State of New York, have invented a new, original, and ornamental Design for a Combination Knife and Fork, of which the following is a specification, reference being had to the accompanying drawing, forming a part thereof, and of which Figure 1 is a view in side elevation of a combination knife and fork showing my new design, and Fig. 2 is a top plan view thereof.

The essential features of my design reside in the blade portion of the combination knife and fork.

I claim:

The ornamental design for a combination knife and fork, substantially as shown and described.

LILLIAN SCHUMACHER.
